UNITED STATES PATENT OFFICE.

ALBERT H. REID, OF DENVER, COLORADO.

ADVERTISING DEVICE.

1,158,849.

Specification of Letters Patent.

Patented Nov. 2, 1915.

Application filed April 22, 1913. Serial No. 762,779.

To all whom it may concern:

Be it known that I, ALBERT H. REID, a citizen of the United States, residing at Denver, in the county of Denver and State 5 of Colorado, have invented certain new and useful Improvements in Advertising Devices, of which the following is a specification.

My invention relates to a combined advertising device and cigar cutter and its principal object resides in the provision of a machine of simple construction in which a number of advertisements arranged in an endless series are successively displayed by 15 the operation of a mechanism in coöperative association with a cigar cutter.

In proceeding in accordance with my invention I provide a cutter adapted to sever the point of a cigar which is pressed into an 20 opening in a movable part of a casing in which the operative parts of the apparatus are inclosed. One of a pair of rotary drums which carry an endless chain to which the advertisements are attached in successive order, 25 is operatively connected with the part above referred to so that when by pressure on the cigar the said part is actuated, the drum with which it is connected will be rotated through an arc of predetermined 30 length. The casing is provided with an opening through which the advertisements placed on the endless chain are separately 35 displayed and when by action of the cigar cutting mechanism the drum is partially rotated, the endless belt is advanced a corresponding 40 distance to move the advertisement appearing through the opening in the casing out of register therewith and to carry another one in its place. A different advertisement is thus displayed each time the apparatus 45 is used to cut the point off a cigar, and the device aside from its value as a commodity in cigar stores, may thus be made a source of profit without much increase in the cost of its production and without any 50 change in the method of its use over ordinary cigar cutters of the same type.

To prevent mischievously inclined persons from deranging the operating mechanism of 55 the machine by operating the same without

the use of a cigar, a means has been provided which normally locks the movable part of the casing in its position of rest and which can unlock it only by the insertion of a cigar in the opening provided for the purpose of cutting its point. 55

In addition to the above mentioned features of the invention, a simple contrivance is provided to automatically limit the intermittent movements of the rotary drums to 60 the arc necessary to move the advertisements on the endless chain, the required distance.

The above described objects are attained by the mechanism illustrated in the accompanying drawings in the various views of 65 which like parts are similarly designated, and in which,

Figure 1 represents a vertical section through the machine, parts of one of the drums and the endless chain having been 70 broken away to reveal the members of the operating mechanism situated behind the same, Fig. 2, a fragmentary view of the casing and parts of the drum operating mechanism showing the position of the contrivance 75 for locking the drum against excessive movement, while the apparatus is in operation, Fig. 3, a vertical section taken along the line 3—3, Fig. 1, and Fig. 4, a similar section taken along the line 4—4, Fig. 1. 80

Referring to the drawings in detail, the reference numeral 2 designates a rectangular casing which comprises an upright portion 3 and a portion 4 which projects forwardly at the lower end thereof. The upright part 3 has at its upper end a sight opening 5 through which in practice the advertisements are displayed, and the other part 4 has an opening that is closed by means of a lid 6 which is hinged to the casing as at 7. The lid is composed of a top plate which has an aperture 8 for the insertion of a cigar, and which along its front and side edges has downwardly extending flanges 9 and 10 which are fitted to move 95 inside the corresponding sides of the forward portion of the casing contiguous to the interior surfaces thereof. One of the side flanges 10 of the lid is extended at its rearward end and the extension which in the 100

drawings is designated by the numeral 12, is formed to provide a toothed segment 13 concentric to the axis of the hinge 7 which connects the lid to the casing. A spring 54 secured to the pintle of the hinge, bears against the under surface of the lid to return it to its normal position after it has been depressed by means of a cigar inserted in the opening 8.

10 A plate 14 which has an opening 15 in axial alinement with the opening 8 in the top plate of the lid, is vertically movably mounted between the side flanges 10 of the same by means of screws 16 which project 15 through longitudinal slots in its angularly bent end portions 17. Springs 18 secured to the flanges 10 engage the lower ends of the end portions 17 to yieldingly maintain the plate at the proper distance from the lower 20 surface of the lid, and a knife 19 is disposed to slidably move in the space between the said surface and the said plate for the purpose of cutting the end off a cigar inserted in the alined openings 8 and 15 during 25 downward movement of the lid. The knife 19 which rests upon the plate 14, is articulately attached at the upper end of a rocker arm 20 which at its opposite extremity is pivotally mounted on a standard 121 erected 30 on the bottom plate of the casing and which in the operation of the device, serves to impel the knife across the openings between the top plate of the lid and the plate 14 when by pressure exerted on a cigar inserted 35 in the said openings the lid is moved about its hinge.

A pair of arms 21 which are yieldingly maintained in their normal position by means of springs 22, are pivotally mounted 40 in bearings 23 on the bottom of the casing and they have at their upper ends, lateral projections 24 which by engagement with the side flanges 10 of the lid, normally lock it against downward movement. The flanges 45 10 are provided with obliquely extending guide-ways 25 through which the projections 24 move during downward movement of the lid and the end portions 17 of the plate 14 are beveled at one of their corners, 50 as shown at 26, in correspondence with beveled enlargements 27 at the upper ends of the arms 21 with which they are normally in engagement.

The advertising element of the invention 55 comprises two equilaterally polygonal drums 28 and 29 which for lightness and cheapness of construction are preferably composed of two circular disks 30 connected by rods 31 which are equidistantly arranged 60 in circles concentric with the disks. The drums are fixedly secured upon shafts 32 and 33 and they are mounted to rotate about horizontal axes in the upper and lower portions of the upright part 3 of the

casing, by means of boxes 34 which are attached to the sides of the casing and in which the ends of the shafts are rotatably supported. The endless chain 35 which is mounted on the two drums is composed of articulately connected plates 52 which in size correspond with the sides of the drum with which they engage. In this connection it will be understood that in mentioning the sides of the drum, reference is had to the areas bounded by the inner surfaces of the 75 two disks and the rods with which the latter are connected.

The articulate connections between the plates 35 are established by means of pintles which extend through axially alined knuckles 36 formed alternately at the adjacent edges of the plates. The knuckles are open at their inner ends and slightly extended along the surfaces of the plates to provide recesses for the reception of advertising 85 cards 37 which in practice, are mounted upon the plates to appear through the sight opening 5 at the upper end of the casing, the portion of the casing in which the said opening is formed, extending obliquely in 90 substantial parallel relation to the adjacent side of the upper drum when the latter is in its normal position of rest. A gear wheel 38 which is loosely mounted upon the shaft 33 of the lower drum is engaged by the 95 toothed segment 13 on the off-set extension 12 of the side flange 10 of the lid 6, and it carries a gravity pawl 39 which engages the teeth of a ratchet wheel 40 which, together with a periphery notched wheel 41, is fixedly mounted on the same shaft between the gear 38 and the adjacent side of the casing. The notches 42 of the wheel 41 are equidistantly arranged along its periphery and correspond in number with the sides of the 105 drum. A dog 43 which is slidably mounted on a longitudinally slotted and recessed plate 44 which is secured to a side of the casing, has an extremity adapted to enter the notches of the wheel and it is held in engagement with the latter by means of a coiled spring 45 disposed in the recess of the plate. A pawl 46 which is pivotally attached to a lateral arm 47 of the sliding dog 110 is held in contact with the peripheral edge 115 of the extension 12 of the flange 10 by means of a spring 48, and the said extension is provided with a single tooth 49 which is formed separate from the segmental gear 13, and which during upward movement of the 120 said extension, engages the end of the pawl 46 which is held against independent upward motion by means of a stop 50 on the lateral arm of the dog 43.

Having thus described the mechanical 125 construction of my invention, its operation is as follows: When the parts are in their normal positions of rest, the lateral projec-

tions on the arms 21 engage the lower ends of one of the sides of the guide-ways 25 on the side flanges of the lid to hold the latter against downward motion, the two polygonal drums are positioned so that one of the sides of the upper one extends parallel to the portion of the casing in which the sight opening 5 is formed and the end of the sliding dog 43 occupies one of the notches in the wheel 41 to hold the advertising element against rotation. When the point of a cigar is inserted in the aperture 8 of the lid, a pressure exerted on the same will first of all cause the plate 14 to move downwardly against the action of the springs 18 and by the engagement of its beveled edges 26 with the beveled enlargements 27 of the arm 21, the latter are moved about their pivots to bring their projections 24 in register with the mouth of the oblique guide-ways 25. The lid thus being free to move downwardly is pushed down by continued pressure on the cigar with the result that the knife is moved through the space between the lid and the plate 14 to sever the point of the cigar. During the consequent upward movement of the extension 12 of the lid, the dog 43 is moved out of the notch in the wheel 41 by the engagement of the tooth 49 with the end of the pawl 46 and the gear-wheel 38 is moved idly on the shaft 33 until the pawl 39 comes in contact with the adjacent tooth of the ratchet wheel 40, when its rotary movement is communicated to the drum. The rotary movement of the drum is converted into a longitudinal movement of the endless chain and a corresponding rotary motion of the upper drum, with the result that the advertisement which appeared in front of the sight opening 5 is moved out of register therewith and the one disposed on the next plate of the chain is carried in the place thereof. During the continued upward movement of the segment, the tooth 49 disengages the end of the pawl 46 and the dog is by the action of the spring 45, as well as by its own gravitational tendency, moved in contact with the peripheral edge of the wheel 41 along which it rides until the next notch of the wheel is moved in register with its end to lock the drum against further rotation. When subsequently the lid is released from pressure, the spring 14 will immediately return it to its normal position and all the parts of the mechanism will automatically reassume the positions they formerly occupied. The contrivance which locks the drum against rotation not only prevents accidental displacement of the chain 35 while the machine is not in use, but also limits the rotary movement of the drums to the precise arc required to move the plate appearing in front of the opening clear of the same, and carry the next one in

its place. The means for locking the lid 6 against downward movement effectively prevents the operation of the mechanism by any force other than that exerted on a cigar inserted through the opening 8 of the lid and the advertisements attached to the chain 35 may be changed as often as desired through an opening in the rear side of the casing which for this purpose has been provided with a door 51.

Having thus described my invention what I claim and desire to secure by Letters-Patent is:

1. In combination, a rotary drum, an endless display element mounted thereon, an operating lever, means for transmitting a movement of said lever to the drum, a wheel having equidistant peripheral notches, mounted for rotation with the drum, a locking device including a sliding dog adapted to enter the notches of the wheel for locking the drum against rotation, and to ride along the peripheral portions of the wheel between its notches, and a spring-held pawl carried on said dog, the said lever having a detent which, during the initial part of its movement, engages the pawl for moving the dog out of a notch of the wheel and which at a determinate point in the movement of the lever, releases the pawl, to permit the dog to move into engagement with the periphery of the wheel.

2. In combination, a rotary drum, an endless display element mounted thereon, an operating lever having a segmental rack and a detent separate therefrom, a gear-wheel mounted for independent rotation, coaxial with the drum, a notched wheel and a ratchet-wheel mounted for rotation with the drum, a pawl on the gear-wheel disposed to engage the teeth of the ratchet-wheel, and spaced from the same when the drum is at rest to permit of a limited free movement during the initial part of the rotation of the gear-wheel, a movable dog capable of entering the notches of the wheel and of riding along the peripheral portions of the same between its notches, a pawl on said dog, disposed to be engaged by the detent of the lever during the initial portion of the movement of the latter for moving the dog out of a notch of the notched wheel, and to be released at a determinate point in the said movement, thereby permitting the dog to engage the periphery of the notched wheel.

3. In combination, a movable endless display element, an operating lever, mechanism for transmitting a movement of said lever to said element at a determinate point in the movement of the lever, a device normally locking the element in its normal condition of rest, and adapted to automatically relock the same, after it has been released, at the termination of a movement of the element

of predetermined extent, the said lever and the said device having coöperative means which effect a movement of the device to unlock the element prior to the effective action 5 of said transmission mechanism on the element, and which during continued movement of the lever in the same direction release the device for its said automatic action

before the element has completed its said predetermined movement. 10

In testimony whereof I have affixed my signature in presence of two witnesses.

ALBERT H. REID.
